D. D. JOHNSON.
VENDING DEVICE.
APPLICATION FILED NOV. 1, 1915.

1,188,452.

Patented June 27, 1916.

UNITED STATES PATENT OFFICE.

DELLEVAN D. JOHNSON, OF FOND DU LAC, WISCONSIN, ASSIGNOR TO JAMES D. GILLESPIE, OF FOND DU LAC, WISCONSIN.

VENDING DEVICE.

1,188,452.

Specification of Letters Patent. Patented June 27, 1916.

Application filed November 1, 1915. Serial No. 58,971.

To all whom it may concern:

Be it known that I, DELLEVAN D. JOHNSON, a citizen of the United States, residing at Fond du Lac, in the county of Fond du Lac and State of Wisconsin, have invented 5 certain new and useful Improvements in Vending Devices, of which the following is a full, clear, concise, and exact description, reference being had to the accompanying 10 drawings, forming a part of this specification.

My invention relates to vending devices and has for its object the provision of a device of this class which is attractive in appearance and which is economical to manufacture.

I contemplate the provision of a device which can be placed upon the counter of a store and which can be operated by a pur- 20 chaser if the proprietor or clerk is busy with other matters. To notify the proprietor that the vending device has been operated I provide a sound producer, or bell, which is arranged to be hit by the articles as they 25 are emitted from the device.

My device is particularly applicable as a collar button vending device and a novel feature of this invention is the provision of means whereby the collar buttons are se- 30 curely held in apertures contained in one of the walls of an easel casing.

My device will be more clearly under- 35 stood by referring to the accompanying drawings, in which—

Figure 1 is a perspective view of the de- 40 vice of my invention. Fig. 2 is a longitudinal cross sectional view taken along the line 2—2 of Fig. 1 and looking in the direction indicated by the arrows. Fig. 3 is a detail view of the lower part of the easel, the outer 45 wall or cover being removed. Fig. 4 is an enlarged cross-sectional view of a portion of the front wall showing the manner of se- 50 curely holding the collar buttons. Fig. 5 is a front view of the front wall with the outer layer of pasteboard removed; and Fig. 6 is a side elevational view of the plug used for disengaging the collar buttons from the easel.

Similar characters of reference refer to 55 similar parts throughout the several views.

The easel comprises a casing 7 formed of pasteboard, or other suitable material, which has secured to its rear face a support 60 the lower end of which is connected by a

flexible strip 9 to the lower end of the cas- 60 ing 7. The support 8 has secured to it by means of a paper strip 10 a brace member 11 which, when the support is in the posi- 65 tion illustrated in Fig. 1, extends forwardly against the rear wall of the casing 7 and holds the support 8 in the position illus- trated.

The side walls of the casing 7 are pro- 70 vided with wooden strips 12 to which is 75 nailed, or otherwise secured, the front face or cover 13. This cover is composed of sev- 80 eral strips of paper and pasteboard, as will 85 subsequently be described. The cover 13 is provided with a plurality of apertures indi- 90 cated at 14—14, each adapted to receive a collar button 15—15 to be vended. These 95 apertures may be made of different sizes so as to accommodate different sized collar but- 100 tons, as illustrated in Fig. 4. Secured to the rear wall of the casing 7, as illustrated in Fig. 3, is a pair of deflectors 16—16 which extend from the side wall of the cas- 105 ing to a point near the center thereof. Car- 110 ried by the rear wall of the casing and dis- posed between the deflectors 16—16 is a sound producer, or bell, 17 positioned slightly above an outlet opening 19 provided in the lower end of the cover 13. A third deflector may be employed if desired at 20, 115 positioned directly above the bell 17 and ex- 120 tends downwardly on each side toward the deflectors 16.

I will now describe the means I employ 125 for holding the collar buttons in place in the 90 wall 13. This wall is composed of two 95 layers 21 and 22 of pasteboard which are glued together to form one piece, as illus- 130 trated in Fig. 4. Extending transversely 135 of the casing and under the heads of two 140 rows of collar buttons is a strip of paper 23 145 which is glued to the member 22. A simi- 150 lar strip 23' is provided between each two 155 rows of collar buttons. The members 21 160 and 22 are, of course, provided with aper- 165 tures through which the collar buttons are 170 arranged to extend. A third pasteboard 175 member 24 is glued to the paper strips 23 180 and 23' and contains apertures which ac- 185 commodate the heads of the collar buttons. 190 The collar buttons are, therefore, held se- 195 curely in place and cannot be removed un- 200 less the paper strips 23 are torn.

In assembling the front wall and collar 205 buttons the pasteboard members 21 and 22 210

are first glued together, then the collar buttons are inserted, as illustrated in Fig. 2, and the paper strips 23 glued into position. The outer pasteboard member 24 is 5 then glued to the paper strips and the cover 13 completed and ready to be secured to the casing 7.

When a collar button is to be emitted from the device the plug 25, illustrated in 10 Fig. 6, is pressed against one of the collar buttons so that the portion of the paper strips 23 which is immediately adjacent the pressed collar button becomes torn and permits the head of the button to pass through 15 the aperture. The button is then free to travel downwardly until it hits the deflector 16 which causes it to hit the bell 17 and to drop through, or in front of, the outlet opening 19. The proprietor is, therefore, 20 notified every time an article is taken from the easel.

Having thus described my invention, what I claim as new and desire to secure by Letters Patent of the United States is:

- 25 1. A vending device comprising a casing, a plurality of articles to be vended carried by the front wall thereof, and a bell carried by the casing and disposed below the articles, each of the articles being arranged when released from the front wall of the casing to travel downwardly by the force of gravity through the interior of the casing and strike the bell to sound an alarm.
- 30 2. A vending device comprising a casing provided with an outlet opening, a plurality of articles to be vended carried by the front wall of the casing, a bell carried by the cas-

ing disposed below the articles, and deflectors positioned between the bell and the articles, each of the articles being arranged 40 when released from the front wall of the casing to travel downwardly by the force of gravity through the interior of the casing, strike the bell to sound an alarm and travel to the outlet opening.

3. A collar button vending device comprising, a casing having the front wall made up of two boards, each provided with several rows of registering apertures, and a plurality of strips between the boards, 50 each disposed between two rows of apertures, the width of each strip being slightly greater than the distance between the two rows so as to extend across the apertures to hold the collar buttons in place.

4. A collar button vending easel comprising, a wall made up of two boards, each provided with several rows of registering apertures, each registering pair of apertures being arranged to receive the head and shank of a collar button, said buttons being arranged to be removed base first from the wall, and a plurality of paper strips carried between the boards, each disposed between two rows of collar buttons 60 and extending between the head and base portions thereof in the paths of the head portions.

In witness whereof, I hereunto subscribe my name this 26 day of October, A. D. 1915. 70
DELLEVAN D. JOHNSON.

Witnesses:

ALONZO PORTLANCE,
WILLIAM E. BOMBAY.
